Primary Examiner — Elizabeth J Oswecki*Assistant Examiner* — Lacey Chey Bowman(74) *Attorney, Agent, or Firm* — Young Basile Hanlon & MacFarlane, P.C.(57) **CLAIM**

The ornamental design for a camera door, as shown and described.

DESCRIPTION

FIG. 1 is a front, top, right perspective view of a camera door showing our new design;

FIG. 2 is a rear, bottom, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The dash-dash, even length broken lines represent unclaimed portions of the camera door and form no part of the claimed design.
